ACID DISPENSER

Olaf L. Chapman, Marshfield, Mo.

Application September 18, 1940, Serial No. 357,326

1 Claim. (Cl. 226—104)

This invention appertains to new and useful improvements in dispensing apparatus and more particularly to a safe dispenser for dispensing acid and other dangerous substances.

The principal object of the present invention is to provide an apparatus for dispensing acid or other dangerous substances in certain predetermined amounts and into receivers in such a manner that none of the substance can spill or in any way escape, and to the end that a multitude of tests, such as in ascertaining the butterfat content of cream, etc., can be made simultaneously.

Another important object of the invention is to provide a dispenser of the character stated which is substantially foolproof.

Another important object of the invention is to provide an apparatus of the character stated wherein the parts are positive acting and not susceptible to the ready development of defects.

These and various other important objects and advantages of the invention will become apparent to the reader of the following specification.

In the drawings:

Figure 1 represents a front elevational view of the dispenser with a portion in section.

Figure 2 is a side elevational view of the dispenser with a portion in section.

Figure 3 is an enlarged fragmentary detailed sectional view showing one of the cylinders in dumping position.

Figure 4 is a top plan view of the tray.

Figure 5 is a section on the line 5—5 of Figure 4.

Figure 6 is a perspective view of one of the cushion disks.

Figure 7 is a side elevational view of one of the cylinders with a portion in section.

Figure 8 is an end elevational view of one of the cylinders.

Figure 9 is a side elevational view of one of the cylinder sleeves with a portion in section.

Figure 10 is an end elevational view of one of the sleeves.

Referring to the drawings wherein like numerals designate like parts, it can be seen that the dispenser consists of an upper glass jar 5 having a filler neck 6. On this neck 6 is a cap 7 having a vent 8.

Numeral 9 denotes a glass plate of substantial thickness located below the bottom of the jar 5. A resilient packing gasket 10 is interposed between the bottom of the jar 5 and the plate 9.

A supporting frame is provided and consists of a box-like base made up of a front wall 11,

side walls 12 and a back wall 13 and from the corners of this box-like structure rises the posts 14. The posts are connected at their upper portions by an upper front wall 15, side walls 16 and a rear wall 17 and these upper walls are bridged by a cover plate 18 secured to the upper walls by screws 19, this cover 18 being formed with an opening through which the neck 6 and cap 7 can protrude. It is to be understood that the box-like structure forming the base portion of the dispenser, the post 14 and the upper walls and cover plate 18 are all of hard rubber, preferably.

It can also be seen in Figures 1 and 2, that the posts 14 at their upper portions are reduced at their inner sides to receive the corner portions of the jar 5 and plate 9, the plate 9 resting at its corner portions on the shoulders 20 of the posts 14.

As can be seen in Figure 1, the opposed portions of the jar bottom 5 and the plate 9 are bored to receive a plurality of parallel sleeves 21. These sleeves as shown in Figure 9 are of glass, each having a row of openings 22 at its upper portion and a row of somewhat larger openings 23 at its lower portion, and the forward end of each of these sleeves 21 is provided with upwardly and downwardly extending lugs or tongues 24 which are received in recesses in the bottom of the jar 5 and plate 9 to prevent rotation of the sleeve 21.

As can be seen in Figures 2 and 3, the openings 22 in each sleeve 21 register with a corresponding port 25 in the bottom of the jar 5, while each large opening 23 in the bottom of the sleeve is opposed to a funnel-like port 26 extending downwardly through the plate 9. The bottom side of the plate 9 at the outlet of each of the funnel-like ports 26 is formed with a channel 27 circumventing the port openings to define a depending skirt 28 which can depend into the neck A of a vial or other container B.

As can be seen in Figures 3 and 7, an elongated cylinder 29 is disposed in each of the sleeves 21 and each of the cylinders 29 has a plurality of pockets 30 therein, equal in number to the number of openings 22 in the corresponding sleeve 21. These cylinders 29 are also of glass and each has a shank 31 projecting from its forward end over which an apertured block or knob 32 is fitted a pin 33 being suitably extended through the shank 31 in front of the block or knob 32 to hold the same definitely in place. Obviously, the knob 32 is used to rotate the cylinder 29 to invert the pockets 30 from the posi-

tion shown in Figure 1 to the position shown in Figure 3 so that the contents can be dumped into the funnel-like ports 26 to flow into the vials or other receptacles B.

It can also be seen that a cross-bar 34 is provided at the front side of the apparatus and overlaps the upper lugs 24 so that there is no likelihood of the sleeves being permitted to rotate or become dislodged from the position shown in Figure 2.

A screw shaft 35 has its ends journalled in the front and rear walls of the lower box-like base of the frame and the forward end is equipped with a crank 36 whereby the shaft can be rotated.

The removable bottom 37 of the box-like base has upstanding flanges 38 to which certain ends of link members 39-39 are pivotally secured. These link members 39-39 are part of a lazy tong arrangement which enclose a pair of nuts 40-40 to which the remaining ends of the links 39-39 are pivotally secured. This lazy tong assembly further consists of a pair of links 41-41, certain ends of which are pivotally secured to depending flanges 42 on a follower plate 43 with the remaining ends of the links 41 being pivotally secured to the nuts 40.

The screw 35 has right and left hand threads 44, 45, and obviously, when the shaft 35 is rotated by the handle 36, the nuts 40 are separated or brought together, depending upon the direction of rotation, for the purpose of raising or lowering the follower plate 43.

On the follower plate 43 is a tray 46 which has a plurality of pockets 47 therein for receiving the base portions of vials C or other receptacles. In each of these pockets 47 of the tray 46 is a cushion disk 48 for supporting the corresponding vial B. The forward end of the tray 46 is provided with a handle 49 so that the same may be

readily slid forwardly on the follower plate 43 when the plate 43 has been moved to a lowered position with the upper ends of the vials B removed from the dispensing skirt 28, as substantially shown in dotted lines in Figure 1.

While the foregoing specification sets forth the invention in specific terms, it is to be understood that numerous changes in the shape, size and materials may be resorted to without departing 10 from the spirit and scope of the invention as claimed hereinafter.

Having described the invention, what is claimed as new is:

An apparatus for dispensing liquids into test vials or the like comprising a boxlike casing including a lower open top chamber, a flat bottom liquid containing tank removably mounted in the upper part of said casing and having rows of liquid discharging apertures in the bottom thereof, a horizontally extending plate in the casing below the tank supporting the latter and having rows of funnel shaped discharge ports therein, the rows of discharge ports registering with the rows of discharge apertures, semi-circular grooves in the bottom of the tank and the top of said plate mating and forming horizontal circular bores parallel with and intermediate registering rows of apertures and ports, cylindrical measuring and dispensing cores rotatably mounted in said bores for receiving liquids discharged from said apertures and emptying the same into said ports, a platform at the top of the chamber for supporting vials beneath said discharge ports and vertically movable to elevate the mouths of the vials up to said ports, and means in the chamber operated to move said platform, said casing being open at its sides between said plate and platform to render the vials visible during filling.

OLAF L. CHAPMAN.
